[57] CLAIM

The ornamental design for a vehicle luggage carrier crossrail, as shown and described.

DESCRIPTION

FIG. 1 is a perspective view of a vehicle luggage carrier crossrail showing our new design, it being understood that the broken lines are for illustrative purposes only and form no part of the claimed design;

FIG. 2 is a top plan view thereof;

FIG. 3 is a side elevational view of the right side thereof, the left side being a mirror image of the right side;

FIG. 4 is an end elevational view of the forward end thereof; and,

FIG. 5 is an end elevational view of the rear end thereof.
